ALBUM

John R. Kennedy, Collingswood, N. J., assignor
to National Publishing Company, Philadelphia,
Pa., a corporation of Pennsylvania

Application June 10, 1950, Serial No. 167,470

3 Claims. (Cl. 129—20)

1

This invention relates to an album, and more particularly concerns an album for storing phonograph records and the like.

It has been conventional practice to provide record albums having a plurality of record carrying envelopes. Such albums are convenient for storage and reference purposes in that a plurality of albums may be stored in vertical or upright positions on shelves in a manner similar to that in which books are usually stored. The titles of the recordings may be printed or otherwise represented on the outer surfaces or shelf backs of the albums for ready reference when the albums are so stored. While conventional albums have found wide use as containers for groups of records, these are unduly bulky and expensive for use in storing single records, and are not adapted for advantageous use in storing records having no interrelation as to title or subject matter. For these and other reasons, individual records have ordinarily been stored in simple envelopes stacked upon each other. However when individual records are stored in envelopes, and the envelopes are stacked together, difficulty is encountered in locating any one particular record. Moreover, such envelopes do not ordinarily provide adequate protection to the records from physical shock and individual records stacked one upon another in conventional containers also have a tendency to warp.

It is accordingly an object of this invention to provide a simple inexpensive record album. Another object of the invention is to provide an album having a shelf back for contents identification. Still another object is to provide an album constructed and arranged to minimize breakage and warpage of stored records. Other objects and advantages of the invention, including those derived from simplicity and economy of manufacture will appear hereinafter.

In summary, the invention concerns an album having a cover piece, a record envelope, and a pair of flaps constituting extensions of the envelope, said flaps being affixed to the cover piece and affixed together to form a backbone intermediate the envelope and the cover piece.

Of the drawings:

Fig. 1 represents a view in perspective of an album constituting one embodiment of the invention, the album being illustrated in closed position;

Fig. 2 represents a view of the inside face of the album in open position;

Fig. 3 represents an enlarged sectional view taken as indicated by the lines and arrows III—III which appear in Fig. 2; and

2

Fig. 4 represents an enlarged fragmentary sectional view of the album, taken as indicated by the lines and arrows IV—IV which appear in Fig. 1.

In describing the form of my invention exemplified by the accompanying drawings, specific terms will be employed for the sake of clarity, but it is to be expressly understood that the scope of the invention is not thereby limited, each such term being intended to embrace all equivalents which perform the same function for an analogous purpose.

Having reference to the appended drawings, wherein one embodiment of the invention is shown, the album 20 has a cover piece 21 desirably of rectangular shape and formed of substantially rigid cardboard, plastic, heavy paper or like sheet material. The album 20 also has an envelope 22, desirably formed of paper or other rigid or non-rigid sheet material. The envelope 22 has an inner wall 23 and outer wall 24 which are joined together at the bottom and outer side edges by flaps 25 and 26 respectively. Flap 25 is formed integrally with inner wall 23 and affixed to outer wall 24 as by gluing or the like, while flap 26 is formed integrally with outer wall 24 and is affixed to inner wall 23. The envelope 22 is open at the top for insertion and removal of the record 27.

Formed integrally with inner wall 23, and constituting an extension thereof, is the flap or extension piece comprehensively designated by the number 30. Similarly the flap 31 is integral with outer wall 24. Referring particularly to Fig. 3, flap 30 is bent first at an angle to the inner wall 23, at the inner edge 32 of the envelope 22, forming the flange strip 33 which constitutes one element of flap 30. Flange strip 33 contacts the outer wall flap 31 and then is bent back to form the web strip 34 which is disposed face to face against outer wall flap 31 and constitutes another element of flap 30. The faces of web strip 34 and flap 31 are glued or otherwise affixed together forming a substantially rigid laminar strip 35 which extends from the bottom to the top of the album and constitutes the backbone thereof. Flaps 30 and 31 extend beyond the backbone formed by portions of said flaps, the inner wall flap 30 being bent away from outer wall flap 31 to form flange strip 36. The flap 30 is once again bent at an angle to flange strip 36, at the edge 37, and forms attachment flap 40 which is affixed to back surface 41 of cover piece 21, as by gluing or the like. The flap 31 also extends beyond laminar strip 35 and terminates in an attachment flap 42 which is simi-

larly secured to front surface 43 of cover piece 21. Flap 31 is desirably pre-folded or scored along the lines 44, 45 which extend from top to bottom along the edges of the laminar strip 35.

It will be observed that the laminar strip 35 which constitutes the backbone of the album has a flat outside surface 46, which may alternatively have a curved contour, on which the title of the record may be printed or otherwise marked. Moreover, the boundary of the laminar strip 35 which corresponds to the position of score line 45 serves to define the inner boundary for the record carrying compartment of envelope 22.

Referring particularly to Fig. 4, it will further become apparent that flange strips 33 and 36 fold against the inner surface of the backbone when the album is closed, thereby contributing further bracing action and adding to the strength and rigidity attributable to the laminar strip 35. The backbone or laminar strip 35 extends at a substantially right angle to the envelope and to the cover piece when the album is arranged in closed book position.

By reason of the structure of the album, as is apparent from Fig. 4, the record 27 when inserted into the envelope constitutes stiffening or rigidifying means for the envelope and forms in combination with the envelope a substantially rigid back cover for the album. The combined thickness of the record and envelope walls is preferably substantially equal to the thickness of the front cover 21, thereby providing a symmetrical album of a character capable of protecting the record from breakage and warping independently of the manner in which the records and albums are stored. The double thickness of sheet material represented by inner wall 23 and attachment flap 40 is complemented at the outer edge of the album (see Fig. 4) by inner wall 23 and flap 26.

The album is conveniently formed of only three pieces of starting material. Two pieces of sheet material, constituting the envelope walls and their extensions, are suitably pre-folded or scored and are attached together as described. At this stage the laminar strip 35 is formed. Cover piece 21 is then placed between the attachment flaps 40, 42 and the construction of the entire album is completed by securing these flaps to the cover piece.

The provision of separate walls 23 and 24, attached together at 25, is advantageous as previously discussed and for the further reason that wall 24, which constitutes the back wall of the album, may consist of waterproof or relatively heavy sheet material. However for certain applications the provision of flap 26 is entirely unnecessary and walls 23 and 24 may be formed of one sheet suitably folded at the outer edge.

While I have shown and described in detail the article constituting one form of my invention, it will be appreciated that modifications may be made in the form of the device, including reversals of parts, substitutions of equivalents, and the use of certain parts independently of

others, all within the spirit and scope of the invention as defined in the appended claims.

Having thus described my invention, I claim:

1. A record album comprising one and only one record carrying envelope having a front wall and a back wall, and flaps formed integrally with the front and back walls, said flaps having free ends, the flaps being affixed face to face to each other to form a laminar backbone having one scored edge defining the inner side boundary of the envelope and another scored edge from which said free ends extend, and a substantially rigid cover piece having an edge disposed between the ends of said flaps and abutting said other edge of the backbone, the free ends of the flaps being affixed to opposite faces of the cover piece, said flaps being foldable along both said scored edges of said backbone.
2. A record album comprising a cover piece, a record carrying envelope having a front wall and a back wall, a closed bottom and outer side, an open top, and flaps formed integrally with the inner sides of the front and back walls, the front wall flap having a flange strip extending from the side of the envelope to the back wall flap, a web strip formed integrally with said flange strip and affixed face to face to said back wall flap to form a laminar backbone for the album, and another flange strip formed integrally with said web strip and having an attachment flap affixed to one face of the cover piece, the back wall flap having an attachment flap affixed to the other face of the cover piece, said backbone being foldable along both its edges with respect to said flaps and said envelope whereby said backbone is substantially perpendicular to said front and back walls and to said cover piece when the album is in closed book position.
3. A record album comprising one and only one record carrying envelope having a front wall and a back wall, and flaps formed integrally with the front and back walls, said flaps having free ends, the flaps being affixed face to face to each other to form a laminar backbone having one scored edge defining the inner side boundary of the envelope and having a second scored edge from which said free ends extend, and a substantially rigid cover piece having an edge disposed adjacent the ends of said flaps, said cover piece edge being adjacent said second scored edge of the backbone, and said flaps being foldable along both said scored edges of said backbone.

JOHN R. KENNEDY.
